DESIGN FOR A TOY DOG

Neil T. Albright, Van Nuys, Calif.

Application March 28, 1944, Serial No. 113,054

Term of patent 7 years

(Cl. D34—15)

To all whom it may concern:

Be it known that I, Neil T. Albright, a citizen of the United States of America, residing at Van Nuys, in the county of Los Angeles, State of California, have invented a new, original, and ornamental Design for a Toy Dog, of which the following is a specification, reference being had to the accompanying drawing, forming a part thereof.

Fig. 1 is a side elevational view of a toy dog showing my new design,

Fig. 2 is a top plan view thereof, and

Fig. 3 is a rear elevational view of the toy dog.

I claim:

The ornamental design for a toy dog, as shown.

NEIL T. ALBRIGHT.
